UNITED STATES PATENT OFFICE

MICHAEL O'BRIEN, OF CHICAGO, ILLINOIS

SPINNER SLED

Application filed February 14, 1930. Serial No. 428,429.

The present invention relates to a spinner sled and has for its prime object to provide a structure particularly adapted for the amusement of children whereby they may impart a spinning movement to a sled when coasting thereon.

Another very important object of the invention resides in the provision of a sled of this nature which is extremely simple in its construction, inexpensive to manufacture, strong and durable, easy to manipulate, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a vertical longitudinal section-al view through a sled equipped with my invention and showing the same in operative position.

Figure 2 is a top plan view thereof,

Figure 3 is a transverse vertical section therethrough.

Figure 4 is a fragmentary longitudinal vertical section therethrough with the parts in operative position in full lines, and

Figure 5 is a sectional view taken substantially on the line 5-5 of Figure 1.

Referring to the drawings in detail it will be seen that the numeral 5 denotes a platform with sides 6 depending therefrom which curve upwardly at their front ends 40 and having runners 7 on their lower edges. The structure thus far described is conventional. The platform 5 is provided adjacent its front end with a longitudinally extending slot 8. A rocker shaft S comprises ends 9 which are rockable in the central upper portions of the sides 6 and merge into inwardly and downwardly inclined portions 10 which in turn merge into horizontal portions 11 which merge into the ends of a U-shaped portion 12 the sides of which are

preferably in abutment and this portion 12 forms a fulcrum member on the end of crank formed by the portions 11.

An operating rod 14 is bifurcated at one end and terminates in bearings 15 circumjacent the portion 11. The rod 14 includes an upstanding extension 16 disposed through the slot 8 and this portion 16 merges into a rearwardly directed extension 17 having an upstanding terminal on which is disposed a handle 18.

A spring clip 20 is mounted under the central portion of the platform 5 to receive the rod 17 when the parts are disposed in inoperative position as is shown in Figure 4.

From the above detailed description it will be seen that my improved structure can be installed in a large number of sleds now used by children in a very economical manner because of its simplicity in construction and the limited number of its parts. This sled with my improvement is a human driven device operated by the occupant only in an easy and expeditious manner.

In use of the sled, a child lies in a prone position upon the platform 5, and normally the runners of the sled travel over the icy surface when coasting thereover. When it is desired to place the sled into a spin, the operator pulls backward upon the handle 18 which in turn swings the crank shaft S to an operative position whereupon the fulcrum runner or pivot member 12 engages the icy surface. The operator pulls back upon the handle a sufficient distance to cause the fulcrum runner to lift the runners of the sled above the icy surface and by manipulation of the occupant's legs and body, the sled may be caused to rotate or spin with the member 12 acting as the pivot. It will of course be understood that a certain amount of skill is required on the part of the occupant of the sled in order to provide the necessary balance.

When the occupant desires to go from a spinning to a forward motion it can be easily done by moving the handle forwardly thereby dropping the revolving sled on the ice and then it can be steered in any direc-

tion desired, the same as the average type toy or amusement sled is used at present.

When the sled is decreasing in speed the arm can be again operated very easily because when the handle is drawn back, the point or bottom end of the arm comes in contact with the ice. The slightest forward motion of the weight of the sled and the occupant is sufficient to raise it on the arm and the sled is again in a revolving motion and can again be operated as before and repeated as often as wanted without the occupant leaving the sled. This device, of course, is principally to be used as a toy or plaything for children and can be used on frozen ponds, city parks, school playgrounds or small spaces because it can revolve in its own diameter or length. When it is not desired to use my attachment improvement it will be seen that the handle may be drawn to its foremost position which will cause the rod 14 to engage in the clip 20.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In a sled having a platform supported upon spaced parallel runners, a crank shaft journaled in bearings beneath said platform approximately midway between the ends of the same, a fulcrum member extending angularly from the crank portion of said crank shaft, an actuating link pivoted to said crank shaft for actuating the same to move said fulcrum member to an inoperative position inward of the tread portions of the runners or to an operative position beyond the same, said actuating link extending forwardly and upwardly through a slot in said platform, and a handle on the free end of said link.

2. In a sled having a platform supported upon spaced parallel runners, a crank shaft journaled in bearings beneath said platform approximately midway between the ends of the same, a fulcrum member extending angularly from the crank portion of said crank shaft, an actuating link pivoted to said

crank shaft for actuating the same to move said fulcrum member to an inoperative position inward of the tread portions of the runners or to an operative position beyond the same, said actuating link extending forwardly and upwardly through a slot in said platform, and a handle on the free end of said link, and a resilient clip mounted on the under side of said platform to receive and hold said link in an inoperative position when moved into engagement therewith.

In testimony whereof I affix my signature.
MICHAEL O'BRIEN.
